US00D777137S

(12) **United States Design Patent** (10) **Patent No.:** **US D777,137 S**
Erbeus (45) **Date of Patent:** **** Jan. 24, 2017**

(54) **PART OF HEADSET**

(71) Applicant: **Sony Mobile Communications AB**,
Lund (SE)

(72) Inventor: **Henrik Erbeus**, Goteborg (SE)

(73) Assignee: **Sony Mobile Communications AB**,
Lund (SE)

(**) Term: **14 Years**

(21) Appl. No.: **29/522,800**

(22) Filed: **Apr. 2, 2015**

(30) **Foreign Application Priority Data**

Oct. 3, 2014 (EM) 002550335

(51) **LOC (10) Cl.** **14-01**

(52) **U.S. Cl.**

USPC **D14/205**

(58) **Field of Classification Search**

USPC D14/205, 188, 192; 181/129, 130, 135;
379/430, 431; 381/74, 380, 381, 327, 374,
381/378, 385, 375, 320; 455/90.3, 344,
455/568, 350, 351, 349, 565, 569;
128/864, 865

CPC H04R 25/00; H04R 1/10; H04R 1/1016;
H04R 5/033; H04R 5/0335

See application file for complete search history.

& Sklar, LLP

(57) **CLAIM**

The ornamental design for a part of headset, as shown and
described.

DESCRIPTION

FIG. 1 is a perspective view of a part of headset showing my
new design.

FIG. 2 is a top view thereof.

FIG. 3 is a bottom view thereof.

FIG. 4 is a right side view thereof.

FIG. 5 is a left side view thereof.

FIG. 6 is a rear view thereof; and,

FIG. 7 is a front view thereof.

The opposite interior face of the part of the headset is a
mirror image of the interior face shown in the perspective
view of FIG. 1.

The broken lines form no part of the claimed design.

1 Claim, 3 Drawing Sheets
